UNITED STATES PATENT OFFICE.

GEORGE T. REISS, OF HAMILTON, OHIO, ASSIGNOR TO THE NILES TOOL WORKS, OF SAME PLACE.

DRILLING-MACHINE.

SPECIFICATION forming part of Letters Patent No. 322,969, dated July 28, 1885.

Application filed April 15, 1885. (No model.)

To all whom it may concern:

Be it known that I, GEORGE T. REISS, of Hamilton, Butler county, Ohio, have invented certain new and useful Improvements in Drill-ing - Machines, of which the following is a specification.

This invention has reference to machines for drilling at once a large number of holes in one or more concentric circles.

10 Certain modern car-wheels consist of two webs of metal bolted to the sides of a flange upon the periphery of the hub and to the sides of a flange projecting inward from the tire, a third circle of holes for bolts being sometimes 15 disposed through the webs at some point between the hub and flange. In some cases each circle of holes in such car-wheels contains a different number of holes, and the radius of the circle of the two outer rows changes with 20 the diameter of the car-wheels.

My machine is peculiarly adapted for the drilling of holes in such car-wheels.

My invention will be readily understood from the following description, taken in connection with the accompanying drawings, in 25 which—

Figure 1 is a front elevation of a drilling-machine illustrative of my improvements, the view exhibiting some of the upper portions of the machine in vertical section and also exhibiting the lower portions of the machine in half-vertical section; Fig. 2, a sectional plan of the machine with many parts omitted, taken upon a line a little above the slotted disk Q, 30 which supports the drill-spindles; Fig. 3, a sectional plan of the machine taken at a point just above the chuck F; Fig. 4, a sectional plan of the sliding block V, which carries the central circle of drill-spindles; and Fig. 5 a 35 vertical section through the support of one of the drill-spindles, showing the device for the independent vertical adjustment of one of the drills of the inner circle, the device for that purpose used in the outer circle of drills being 40 similar.

In the drawings, A represents the sole plate of the machine; B, four columns rising therefrom; C, a housing secured to the top of the column and furnishing bearings for the top

shafts; D, a bed provided with V grooves- 50 like a very short bed for a metal-planing machine, and fitted to slide vertically upon the columns; E, a table arranged to slide like a planer-table on the bed; F, a chuck fitted with jaws adapted to grasp a car-wheel or 55 similar article, and arranged to rotate upon the table of the machine, upon which it is supported, a hub upon the chuck being journaled in a central bearing in the table; G, a pinion journaled in the table and engaging a toothed 60 segment on the periphery of the chuck, and adapted, when turned with a wrench, to rotate the chuck a portion of a revolution upon the table; H, a pair of vertical feed-screws 65 projecting downward from the bed, in whose bottom they are journaled, and provided at their upper ends with bevel-gears; J, a horizontal shaft journaled in the bed, and provided with bevel-gears engaging the gears upon the feed-screws; K, a clutch, by which 70 this shaft can be locked against rotation; L, worm-gears journaled in the sole-plate to form the nuts for the feed-screws; M, a horizontal shaft journaled on the sole-plate and provided with worms engaging the worm- 75 gears; N, pulleys, one on each end of the shaft M, fitted to revolve loosely upon the shaft, and provided with clutches by which either one of the pulleys may be locked to the shaft; O, levers pivoted to the sole-plate and having their 80 outer ends connected by links to the bed of the machine, and having attached to their inner ends a counterbalance-weight; P, hinged wings projecting forward from the bed and forming prolongations of the slide-grooves of 85 the bed; Q, a disk rigidly secured to the upper part of the columns and provided with twelve radial slots; R, brackets supporting vertical drill-spindles and fitted to adjust in and out in the slots of the disk; S, radial 90 screws by which these brackets are adjusted in the slots, each screw being provided with, near its outer end, a bevel-pinion; T, an annular bevel-gear surrounding the top of the disk and engaging all of the pinions of the 95 screws S; U, clutches upon each alternate one of the screws S, each serving to lock the bevel-pinion to its screw, the pinions not provided

with clutches being fast upon their screws; V, a cylindrical block supporting a circular series of nine vertical spindles and fitted to slide vertically in the central bore of the disk Q; W, 5 a plate disposed above the block V, and forming a bearing-plate for the nine pinions which drive the central drill-spindles and provided with a central upper hub; X, posts reaching from the top of the disk Q to the plate W, and 10 serving as rigid supports for the plate; Y, a vertical shaft journaled in the top housing, C, and in the hub of the plate W; Z, a spur-gear upon the lower end of this shaft; a, a shaft journaled in the top housing of the machine 15 and provided, near its inner end, with a bevel-pinion; b, a bevel-gear fast upon the vertical shaft Y and engaging said bevel-pinion; c, the drill-spindles of the inner circle; d, pinions, nine in number, journaled in the bearing-plate 20 W, engaged and driven by the spur-gear Z, and serving to drive the central drill-spindles, which are splined to slide vertically through the pinions; e, a second shaft at the top of the machine arranged and provided in a manner 25 like the shaft a; f, a bevel-gear engaged and driven by the bevel-pinion on the shaft e and provided with a downwardly-projecting hub fitted to revolve freely upon the central vertical shaft, Y, and supported vertically by the hub 30 of the bearing-plate W; g, a bevel-gear upon the lower end of the hub of the bevel-gear f; h, the drill-spindles, twelve in number, carried by the brackets R; j, bevel-gears journaled in these brackets and fitted to drive the drill-spindles, which latter are to be splined to the gears; 35 k, horizontally-arranged radial shafts, twelve in number, with their inner ends journaled in the periphery of the hub of the bearing-plate W, and provided with bevel-pinnions engaged 40 and driven by the bevel-gear g, and having their outer portions splined; l, bevel-pinnions journaled in the brackets, engaging and driving the gears j, and fitted to slide upon and be driven by the radial shafts k; m, a counter- 45 balance-weight for the central spindle-carrying block V, the cord or chain of the weight passing vertically through an axial hole in the vertical shaft Y, and over sheaves on the top housing; n, a receiving-pulley upon the outer 50 end of the top shaft, e; p, a similar pulley on shaft a; q, pulleys upon top shafts serving to transmit motion through belts to the pulleys N at the foot of the machine; r, exteriorly-threaded bearing-tubes, one for each of the 55 drilling-spindles, fitted to adjust vertically in bores in the brackets and central spindle-carrying block; t, nuts upon each end of these tubes, and serving to effect their vertical adjustment; u, a rotary disk within the central 60 spindle-carrying block, provided with cam-slots engaging the inner ends of plungers sliding radially in the block, the outer ends of the plungers engaging holes in the bore of the disk in which the block slides, (see Fig. 4;) y, a 65 horizontal shaft whose inner end is bevel-gear to the spindle of the cam-disk u.

Motion is transmitted to the machine by

belts from any convenient driving-shaft to the top pulleys, p and n, so as to revolve the shaft a in one direction and the shaft e in the 70 other direction. The shaft a rotates the central vertical shaft, Y, and, through the spur-gearing Z d, the central circle of drill-spindles, c. The shaft e rotates the drill-spindles of the brackets through the medium of the gears f g 75 l j and the radial shafts k. The pulleys q transmit motion to the loose pulleys N at the base of the machine, the two base-pulleys obviously revolving in opposite directions. The drill-spindles are to be fitted with chucks or sockets 80 to receive the drills adapted for the work in hand. The wings P being opened outward, the table and chuck are pulled forward, and the car-wheel or other article to be drilled is properly secured within the chuck, after which 85 the table is again pushed inward, bringing the chucked work centrally under the system of drill-spindles, the wings P being then folded inward, so as not to interfere with the close approach of the attendant to the work. The 90 work to be drilled being thus properly disposed beneath the drills, the shaft J is turned by a hand crank, thus rapidly elevating the bed D and the matter supported by it to a point within reach of the drills. The proper 95 one of the pulleys N is now clutched to the shaft M, and the shaft J is locked against rotation by means of its clutch K. Under these conditions the bed-work will be automatically fed upward as the drilling proceeds. When the drills are through with this part of their work, motion in an opposite direction is given to the shaft M by releasing the pulley N which has been clutched to it, and clutching to it the other one of the pulleys 100 N. This gives to the bed, &c., a slow automatic descent. If a rapid descent be wanted, both pulleys N are unclutched, the clutch K released, and the bed fed downward rapidly by revolving the shaft J by hand. Through the levers O, 105 with their links and weight, the bed, &c., is counterbalanced and rendered easy of hand motion.

There are in the case illustrated twelve of the outer drill-spindles, h. In case it is desired that the circle of holes driven by these spindles 115 shall contain twenty-four holes, twelve are first drilled in the manner described, and then the bed, &c., is lowered and the chuck properly rotated through the medium of pinion G so as to bring the twelve drilling-spindles to the 120 proper position for the twelve new holes of the circle.

In the case of the car-wheels of the character hereinbefore described, the drill-spindles h are set to drill their holes in the outer circle, and the central spindle-bearing block, V, is locked in its downward position so that the central circle of holes will be drilled simultaneously with one of the outer circles. When the chuck is partially rotated, so as to permit the outer 130 spindles to drill new holes in their circle, the central circle of spindles must be gotten out of the way, so as to remain idle while the new outer holes are being drilled. This is accomplished

by turning the shaft so as to draw the locking-plungers inward, thus permitting the central block with its spindles to be pushed upward, so that the points of the central circle of drills 5 will not come in contact with the work.

The twelve spindles *h* are to be set in a true circle, and this circle can be enlarged or reduced at will by turning any one of the screws *S*, the annular gear *T* transmitting a uniform 10 rotation of all of the screws, thus moving all of the brackets simultaneously. By this means the diameter of the circle of the outer spindles is adjusted to suit car-wheels, &c., of varying diameters.

15 It is obvious that, in case less than twelve holes should be required in the outer circle, or less than nine in the inner circle, certain of the spindles may have the drills omitted, and that in all cases the number of spindles involved in the machine may be the subject of special consideration in designing the machine for special work.

When the outer circle of holes is of comparatively small diameter, or when there is to 25 be an intermediate circle of holes, as mentioned in connection with the car-wheels hereinbefore described, it may be desirable that such comparatively small circle or such intermediate circle contain but half the number of 30 holes of the larger or outermost circle. Provision is, therefore, made for moving alternate spindles of the outer circle of spindles inward or outward simultaneously independent of the other spindles of the outer series.

35 By inspecting Fig. 2 it will be observed that the screws *S* of the alternate brackets are provided with clutches *U*, by means of which the alternate screws can be released from their bevel-pinion which engage the annular 40 gear *T*. These clutches being all released, it follows that the other spindles only partake of the simultaneous motion due to the presence of the annular gear. In this manner six of the spindles can be given a simultaneous radial adjustment, while the other six spindles 45 remain in their old position or in any position into which they may be independently adjusted. The six brackets whose screws are provided with clutches may thus also be adjusted into a circle larger or smaller than the 50 circle of the remaining spindles; and, the clutches being again engaged, the entire system of outer spindles may be adjusted radially together, and in the same manner the clutch-55 provided brackets may be set in any relative radial position desired, either in a true circle or not, and the clutches may then be engaged so that the whole system moves together.

It will be observed in Fig. 2 that the alternate slots of the disk in which the brackets slide reach farther inward than the intermediate slots. By this means the alternate brackets can be moved radially inward to form a very small circle, while still leaving 65 the slots of sufficient width to accommodate brackets of substantial dimensions. If all of the brackets were to be moved thus extreme-

ly inward, the slots would require to be of such limited width as to restrict the width of the brackets to an objectionable degree, and 70 if the bracket-width be properly maintained the circle into which all of the spindles could be adjusted would not be probably of sufficiently small diameter.

In each bore of bracket or central spindle-carrying block is fitted a tube, *r*, within which is formed the bearing for the drill-spindles. This tube is exteriorly threaded and provided with nuts by means of which it can be adjusted vertically and then securely fixed. By 80 this means the drill-spindles are all rendered independently adjustable vertically, so as to accommodate drills varying a trifle in length, as wear or slight breakage at the point takes place, the desire being that all of the drills 85 shall enter the work at once. This arrangement also makes provision for independently adjusting the vertical height of the various drills in case the article to be drilled presents surfaces on different planes. As the 90 bearing-tubes adjust vertically in their bores the spindles slide in the driving-gears, being splined thereto.

It has been stated that the two pulleys *N* serve in rotating the worm-shaft *M* in either 95 direction, according to whether the bed-work is to be raised or lowered by power. As a matter of fact, the bed-work will seldom, if ever, require to be lowered otherwise than by the hand-shaft, and in practice the two pulleys *N* 100 will be driven in the same direction, one of the belts being crossed. This arrangement permits the power-feed to be operated when one of the series of spindles is standing still, as may often be the case where the machine 105 is required for drilling one circle only of holes.

I claim as my invention—

1. In a drilling-machine, the combination of sole-plate *A*, columns *B*, drilling mechanism supported thereby, work-supporting bed *D*, 110 fitted to slide vertically on the columns, elevating-screws *H*, and shaft *J*, geared to the screws, substantially as and for the purpose set forth.

2. In a drilling-machine, the combination of sole-plate *A*, columns *B*, drilling mechanism supported thereby, work-supporting bed *D*, 115 fitted to slide on the columns, elevating-screws *H*, shaft *J*, geared to the screws, and levers *O*, provided with counterbalance-weight and 120 linked to the bed, substantially as and for the purpose set forth.

3. In a drilling-machine, the combination of sole-plate *A*, columns *B*, drilling mechanism supported thereby, work-supporting bed *D*, 125 fitted to slide on the columns, elevating-screws *H*, worm-wheels *L*, forming nuts for the screws, and shaft *M*, provided with worms and with mechanism, substantially as described, for rotating it, substantially as and for the purpose 130 set forth.

4. In a drilling-machine, the combination of sole-plate *A*, columns *B*, drilling mechanism supported thereby, two pulleys, *q*, arranged

- to rotate in opposite directions, the work-supporting bed D, fitted to slide on the columns, elevating-screws H, worm-gears L, forming nuts for the screws, shaft M, provided with 5 worms, and the pulleys N, loose upon the shaft, and provided with locking-clutches, substantially as and for the purpose set forth.
5. In a drilling-machine, the combination of sole-plate A, columns B, drilling mechanism 10 supported thereby, work-supporting bed D, fitted to slide upon the columns, elevating-screws H, shaft J, geared to the screws, clutch K, fitted to lock said shaft against rotation, worm-gears L, forming nuts for the screws, and 15 shaft M, provided with worms and with mechanism, substantially as shown, for rotating it, substantially as and for the purpose set forth.
6. In a drilling-machine, the combination of 20 columns B, drill mechanism supported thereby, bed D, fitted to slide on the columns and provided with horizontal slideways, and table E, fitted to slide upon the bed, substantially as and for the purpose set forth.
7. In a drilling-machine, the combination 25 of columns B, drilling mechanism supported thereby, bed D, fitted to slide upon the columns, and provided with transverse slideways, hinged wings P, forming outward prolongations of the slideways, and table E, fitted to move inward and outward on the slideways, substantially as and for the purpose set forth.
8. In a drilling-machine, the combination 30 of columns B, drilling mechanism supported thereby, bed D, fitted to slide upon the columns, and chuck F, secured to the top thereof, and pinion G, for partially rotating the chuck with reference to the bed, substantially as and for the purpose set forth.
- 40 9. In a drilling-machine, the combination of columns B, drilling mechanism supported thereby, bed D, fitted to slide upon the columns, table E, sliding transversely upon the bed, and chuck F, supported by the table and 45 fitted to revolve thereon, substantially as and for the purpose set forth.
10. In a drilling-machine, the combination of columns B, drilling mechanism supported thereby, bed D, fitted to slide upon the columns, table E, sliding upon the bed, chuck F, supported upon the table and adapted to 50 rotate, and pinion G, arranged to rotate the chuck with reference to the table and bed, substantially as and for the purpose set forth.
- 55 11. The combination of columns B, bed D, fitted to slide upon the columns, disk Q, rigidly secured to the columns and supporting a group of drill-spindles, housing C, secured to the top of the columns, a horizontal shaft 60 journaled in this housing, an axially-arranged vertical shaft, and gearing arranged to transmit motion to this vertical shaft from the housing-shaft, and from this vertical shaft to surrounding drill-spindles, substantially as 65 and for the purpose set forth.
12. In a drilling-machine, the combination of disk Q, outer series of drill-spindles, h, sup- 70 ported thereby, block V, fitted to slide vertically in the disk and be locked thereto, and drill-spindles c, carried by said block, substantially as and for the purpose set forth.
13. In a drilling-machine, the combination of radially-slotted disk Q, brackets R, provided with drill-spindles, screws S, provided with bevel-pinions, and annular bevel-gear 75 T, engaging said pinions, substantially as and for the purpose set forth.
14. In a drilling-machine, the combination of slotted disk Q, brackets R, provided with drill-spindles, screws S, provided with bevel- 80 pinions, annular bevel-gear T, engaging said pinions, and clutches U, fitted to lock the bevel-pinions to their screws, substantially as and for the purpose set forth.
15. In a drilling-machine, the combination 85 of the slotted disk Q, brackets R, provided with drill-spindles, screws S, provided with bevel-pinions, annular bevel-gear T, engaging said pinions, and clutches U upon the alternate ones of the screws S, substantially as and for 90 the purpose set forth.
16. In a drilling-machine, the combination 95 of brackets R, provided with drill-spindles, and disk Q, provided with slots for the brackets, the alternate slots being prolonged inward beyond the inner ends of the intermediate slots, substantially as and for the purpose set forth.
17. In a drilling-machine, the combination 100 of disk Q, block V, sliding vertically in the disk, and cam-disk u, provided with locking-plungers, substantially as and for the purpose set forth.
18. In a drilling-machine, the combination 105 of a series of drill-spindles supported in brackets or a block, bearing-tubes r, forming bearings for the spindles, and nuts t, for adjusting the spindles independently with reference to their supports, substantially as and for the purpose set forth.
19. In a drilling-machine, the combination 110 of an inner circular series of drill-spindles, c, a disk, Q, having a series of radial slots, and an outer series of drill-spindles, h, supported in brackets R, adjustable in the slots of the disk, substantially as and for the purpose set 115 forth.
20. In a drilling-machine, the combination 120 of a circular series of drill-spindles, c, spur-pinions d, spur-gear Z, vertical shaft Y, bevel-gear b, and horizontal shaft a, provided with 125 pulley p, and with a bevel-pinion engaging said bevel-gear, substantially as and for the purpose set forth.
21. In a drilling-machine, the combination 125 of disk Q, block V, carrying a circular series of drill-spindles, bearing-plate W, and posts X, substantially as and for the purpose set forth.
22. In a drilling-machine, the combination 130 of brackets R, provided with drill-spindles, radial shafts k, geared to these spindles, and provided at their inner ends with bevel-pinions, united bevel-gears f g, and shaft e, provided with pulley n, and with a bevel-pinion

engaging bevel-gear *f*, substantially as and for the purpose set forth.

23. In a drilling-machine, the combination of brackets *R*, provided with drill-spindles, 5 radial shafts *k*, bevel-geared to these spindles, and provided at their inner ends with bevel-pinions, a hub on a bearing-plate furnishing bearings for the inner ends of said radial shafts, shaft *Y*, rising from said hub, and united bevel-gears *f g*, bearing upon said shaft, substantially 10 as and for the purpose set forth.

24. In a drilling-machine, the combination of inner series of drill-spindles, *e*, vertical shaft *Y*, geared to the spindles of said series, outer 15 series of drill-spindles, *h*, radial shafts *k*, geared to said outer spindles, and provided at their

inner ends with bevel-pinions, and bevel-gear *g*, encircling the shaft *Y* and engaging the bevel-pinions of the radial shafts, substantially as and for the purpose set forth. 20

25. In a drilling-machine, the combination of sliding block *V*, provided with series of drill-spindles *e*, vertical shaft *Y*, geared to said drill-spindles, and counterbalance-weight *m*, attached to the block *V* by cord or chain 25 passing axially through shaft *Y*, substantially as set forth.
